UNITED STATES PATENT OFFICE

JOHN W. COSGROVE, DECEASED, LATE OF MEDFORD, MASSACHUSETTS, BY CAROLINE E. COSGROVE, ADMINISTRATRIX OF MEDFORD, MASSACHUSETTS, ASSIGNEE TO UNITED SHOE MACHINERY CORPORATION, OF PATERSON, NEW JERSEY, A CORPORATION OF NEW JERSEY

CEMENTING MACHINE

Application filed January 16, 1929. Serial No. 332,901.

This invention relates to cementing machines and is herein illustrated as embodied in a machine for cementing shoe parts.

Machines for applying simultaneously stripes of cement to the opposite faces of a piece of work are extensively used and commonly have been arranged so that the stripes of cement are of substantially equal width. It is found, however, that there are numerous instances in the manufacture of shoes, and in particular in the manufacture of rubber-soled overshoes, where it is desired to apply a narrow stripe of cement to one side of the piece of work and to apply a substantially wider stripe to the other side. Commonly one edge of each stripe coincides with the edge of the work. There is no particular difficulty in changing the rolls of a double cementing machine (by taking out one set and putting in another set) to cause the machine to apply stripes of unequal width, but it has been found, however, that when such an arrangement is used the cement is applied unevenly upon the overhanging margin of the wider stripe because of the lack of support of the work by the narrow applying roll at this point.

Accordingly, one object of the invention is to provide an improved double cementing machine by means of which stripes of cement of uneven widths may be applied in a uniform manner to the opposed faces of a piece of work.

One of the features of the invention resides in a novel cementing machine having a wide upper coating roll and a narrow lower coating roll aligned along one edge, a cement receptacle underlying the lower roll, together with means secured to said receptacle for supporting a piece of work to hold it in contact with the overhanging portion of the wide upper coating roll. In the illustrated embodiment of the invention, a yieldingly mounted arm is arranged alongside the narrow lower coating roll to hold the work up against the upper roll, which arm is arranged to be displaced forwardly and downwardly by contact with a thickened portion of a piece of work, such as a seam.

Leakage of cement around the sides of the

upper roll of a cementing machine in which cement is supplied to the applying roll by means of a receptacle above the roll is somewhat difficult to prevent, more especially if, as is usually the case, the quantity of cement taken out by the upper roll is controlled by means of a slidably mounted scraper adjustable toward and away from the periphery of the roll. The invention provides also a novel scraper mechanism constructed and arranged to control the quantity of cement taken out by the upper roll and to prevent leakage of cement through the joints between said scraper and the casing in which it is mounted.

Still other features reside in work guiding and supporting mechanism associated with the lower roll and enabling the outer edge of the work to be guided across any desired portion of the roll while enabling the work supporting portion of the guiding mechanism to be utilized for controlling the quantity of cement delivered by the lower roll.

These and other features of the invention are more fully described in the following specification taken in connection with the accompanying drawings, in which

Fig. 1 is an end elevation of a double cementing machine embodying the invention;

Fig. 2 is an enlarged fragmentary view of the end of the lower cement roll and associated parts, portions being broken away;

Fig. 3 is an enlarged side elevation of the coacting rolls;

Fig. 4 is a vertical section through the axes of the two rolls, looking at the machine from the rear;

Fig. 5 is a plan view partly in section of the upper roll and its cement controlling mechanism removed from the machine;

Fig. 6 is an end elevation of these parts with parts broken away and in section; and

Fig. 7 illustrates a fragment of a piece of work showing stripes of cement of uneven width applied to the opposed faces of the strip.

The illustrated machine is of the type illustrated in Letters Patent of the United States No. 1,380,360 granted June 7, 1921 upon the

application of John W. Cosgrove, to which patent reference may be had for the description of parts not more fully set forth herein and embodies a frame 10, upper cement receptacle 12 and control handle 14 of the type shown in that patent.

To adapt the machine for coating opposite faces of work, such as the fastener strip 28 of the type used in overshoes or gaiters and shown in Fig. 7, opposed coating rolls 20 and 26 are utilized. Accordingly, the machine has an upper arm 16 (Fig. 3) in which there is journaled a shaft 18 for the upper roll 20 and it also includes a pivoted lower arm 22 in which there is journaled a shaft 24 carrying the lower cement applying roll 26 which takes the place of the work-supporting driven feed roll of the patented machine. A cement receptacle 30 partially surrounds and supplies cement to the lower roll 26 and is secured by screws to the end of the arm 22. A sheet of packing material 32 is interposed between the edges of the cup-like receptacle and the end of the arm 22 to make a tight joint and provision is made for supplying cement to this receptacle from a tank 34 (Fig. 1) through a conduit 36 held by bolts 38 to a flange 40 (Fig. 2) on the lower receptacle 30. It will be understood that the supply tank 34 is of the barometric type and that when it is desired to remove the cement for the night or in order to clean the machine, a valve 42 in the conduit 36 may be opened to drain off the remaining cement.

It will be noted from Fig. 4 that the upper cement roll 20 is substantially wider than the lower roll 26, although the inner lateral faces of the two rolls are in alinement. This leaves a substantial overhanging portion of the upper roll toward the end of the machine where the work is not supported by the lower roll and it is found that, lacking support at this point, the cement would be unevenly applied at the inner margin of the upper stripe. Accordingly, there is provided a supporting arm 50 having an inturned upper end 52 adapted to underlie and to support the work, holding it against a portion of the upper roll 20. This arm 50 is pivotally mounted on the end of the receptacle 30 by means of a screw stud 54 and has a limited swinging movement within a notch 56 (Fig. 2) provided in the upper edge of the lower receptacle 30. A spring 58 secured to the lower end of the pivoted arm 50 (Figs. 1 and 3) tends to hold the upper end 52 of the arm directly beneath the upper roll but allows it to be displaced forwardly and downwardly by a thickened portion of the work as the latter is fed in the direction indicated by the solid arrow in Fig. 1.

In order to assist in feeding the work to the machine along the desired path, there are associated with the lower roll a work table 60 and a work guide 62. The work table 60

serves not only to support the work up to a point close to the bite of the rolls, but is also arranged to serve as a scraper to control the amount of cement delivered by the lower roll. To this end it rests upon an inclined surface 64 (Fig. 2) of the cement receptacle 30 which is substantially tangential to the surface of the lower roll. The forward edge of the table 60 is beveled and may be moved closer to or farther away from the periphery of the lower roll, acting as a scraper to remove surplus cement from the surface of that roll. For convenience of adjustment and in order to hold the combined table and scraper 60 in adjusted position, it is provided with a depending flange 66 having an inclined slot parallel to the surface 64 of the receptacle, through which slot passes a retaining screw 68. This flange rests against a boss 70 which is machined to provide a smooth surface in a plane exactly normal to the axis of the roll so that in all of its adjusted positions the table 60 will act uniformly across the whole width of the lower roll as it scrapes off the surplus cement.

The work guide 62 is provided with a vertical surface 72 acting as an edge gage against which the edge of the work may be positioned as it is guided over the table 60, and fastened to this upright surface 72 is a holdown having an outwardly extending flange 74 tending to prevent curling of the work. The forward corner of this flange is turned upwardly to facilitate entering the work in the machine. One portion of the gage member 62 fits closely against the surface of the table 60 and may be adjusted across this surface to meet the requirements of any particular piece of work which is presented to the machine. To this end the edge gage 62 has a depending slotted arm 76 through which passes a clamping screw 78 to hold it to the lower arm 22 of the cementing machine. It will be understood that the arm 22 is pivoted in the machine and may be lowered when no work is passing through the machine, or may be raised as a piece of work is presented to the machine to bring the two rolls 20 and 26 into contact with the opposite sides of the work 28. The lower roll 26 is provided with lateral flanges to help in holding the cement on the surface of the roll and has a series of frusto-pyramidal studs arranged over its surface to help to carry a sufficient body of cement. The roll 26 is removably mounted on the end of the shaft 24.

In common with the machine disclosed in United States Letters Patent No. 1,380,360, referred to above, the upper roll 20 is detachably mounted on its shaft 18 and is held within a removable casing 80 provided with a supporting stud 82 which fits tightly within a socket provided in the upper arm 16 of the machine and is clamped in position by means of a clamping screw 84. However, to

assist in removing the casing from the machine after the clamping screw has been loosened, there is herein provided an opening 86 in the arm 16 in which may be inserted a suitable tool in the nature of a screw driver to pry against the end of the stud 82 and the latter is also provided with a series of slots 88 to give a bite for the prying tool after the stud has been partly removed from its socket.

10 Looking toward the prevention of leakage of cement across the lateral faces of the roll 20, the casing 80 is provided with side plates 90, 92 each of which is recessed to receive a felt insert 94 and these plates are pressed against the sides of the roll by means of a screw 96 threaded in the casing. In the herein described machine, the quantity of cement carried by the upper roll is determined by a horizontally arranged scraper 100 guided 20 in a path parallel to and adjacent to the lower edges of the casing 80. Although it is possible to use a great variety of rolls in a machine of this type with satisfaction, it has been found that one particularly appropriate 25 form is that illustrated in the drawings in which the surface of the roll is provided with a series of closely adjacent circumferential V-shaped grooves. By thus greatly increasing the peripheral surface, the quantity of 30 cement carried by the roll may be substantially increased without dripping. For the proper control of the quantity of cement carried out by this form of roll, the forward end 101 of the scraper 100 is similarly grooved 35 almost to fit the grooved surface of the roll 20. In any event, the forward end of the scraper is U-shaped, being ground away to provide a slot between forwardly extending side arms 102 which are arranged closely to 40 engage the sides of the roll completely to clean cement from the lateral surfaces of the roll adjacent to the periphery. The side plates 90 and 92 are notched at 104 to receive these projecting arms 102. The notches 104 45 extend all the way through the side plates 90, 92 so that adjustment of the screw 96 will not cause the plates 90 and 92 to bind the scraper. On the other hand, these plates fit closely 50 against the top and bottom faces of the scraper arms 102 and prevent leakage at this point. Adjustment of the position of the scraper to control the quantity of cement delivered by the upper roll 20 is effected by 55 means of an adjusting screw 106 threaded in the casing 80 and rotatably held in a slot of the upturned end 108 of the scraper 100. A stop screw 110 is mounted in this upturned end to limit the inward movement of the scraper so that it cannot be jammed against the surface of the roll to cause undue wear or 60 breakage.

Leakage of cement between the scraper 100 and the casing 80 is also effectively prevented 65 by providing the sides of a thickened portion

103 of the scraper with inwardly extending grooves 111 (Fig. 6) to receive tongues 112, 112 (Fig. 3) formed upon the inner faces of the casing. These tongues and grooves are each of rectangular shape so as to provide a plurality of angularly related contacting faces in any leakage path between the receptacle and the outer air. Without being machined within such fine limits as to make the cost of the machine prohibitive, these faces form an effective barrier to the leakage of cement.

70 The piece of material from which the scraper 100 is formed may readily be ground away to provide a medial slot at its inner end between forwardly extending side arms 102, which slot will be of such dimensions that the side arms engage closely against the sides of the roll. The operation can be performed with considerable accuracy without involving any large cost. It will be seen, therefore, that the described construction effectively prevents leakage not only through any joints between the scraper and the casing, but also 75 between the sides of the roll and the forwardly extending arms of the scraper as well as between the leakage-preventing plates 90, 92 and the scraper arms 102.

80 In spite of all precautions, a small quantity of cement may find its way on to the lateral surfaces of the roll 20 and in order to facilitate the return of this cement to the receptacle, the side plates 90, 92 are cut away as indicated by the inclined line 116 in Fig. 5 and by the inclined line 118 in Fig. 6 to provide a tapered passage through which the cement will be continually packed back into the receptacle as it is scraped from the lateral surfaces of the roll and brought to a point 120 (Fig. 6) adjacent to the upper rear side 85 of the roll.

90 In the use of the machine, supposing that the receptacles 12 and 34 have been filled with cement, the operator will insert a piece of work (which may, of course, have more than the single thickness illustrated) beneath the holdown 74 and against the edge gage 72 and, starting the machine by the control handle 14, will raise the lower arm 22 by means of a treadle (not shown) connected to a treadle rod 122 (Fig. 1). A portion of the work opposed to the overhanging portion of the wider roll 20 will be supported by the yielding arm 52 which will hold this portion of the work in sufficiently firm contact with the upper roll so as to insure a proper coating of cement. The control of the quantity of cement delivered by the lower roll 26 is effected by adjustment of the combined work table and scraper 60, and the control of the quantity of cement delivered by the upper roll 20 is effected by the adjustment of the scraper 100.

100 Having thus described the invention, what 130

is claimed as new and desired to be secured by Letters Patent of the United States is:

1. In a double cementing machine, a wide upper cement applying roll, means for supplying cement to the upper roll, a narrow cement applying roll underlying a portion of said upper roll, a receptacle underlying said lower roll to supply cement thereto, and means secured to said receptacle and supporting a portion of the work in contact with the wide roll where it overhangs the narrow roll.
2. In a double cementing machine, a wide cement applying roll to apply a stripe of cement to the upper surface of a piece of work, a narrow cement applying roll to apply a narrow stripe of cement to the lower side of a piece of work in opposed relation to said other stripe, means for supplying cement to said rolls, and a pivoted work-supporting arm for holding the work in contact with the overhanging portion of the upper roll where it is not opposed to the lower roll.
3. In a double cementing machine, superposed cement applying rolls, the upper one of which is wider than the lower, means for supplying cement to said rolls, and a yielding work-supporting arm for supporting the work in contact with the upper roll at that portion of its width where it overhangs the lower roll.
4. In a double cementing machine, superposed cement applying rolls, the upper of which is wider than the lower and overhangs the lower, means for supplying cement to said rolls including a receptacle underlying and partially surrounding the lower roll, and a pivoted arm mounted on said receptacle for holding the work in contact with the overhanging portion of the upper roll.
5. In a double cementing machine, superposed cement applying rolls arranged progressively to coat a piece of work fed between the rolls, said upper roll being wider than and overhanging the lower, means for supplying cement to said rolls including a receptacle underlying and partially surrounding the lower roll, a pivoted arm mounted on said receptacle for holding the work in contact with the overhanging portion of the upper roll, a spring tending to swing the upper end of said pivot arm in a direction opposite to the direction of feeding movement of the work, and means for limiting said swinging movement.
6. In a cementing machine, a cement applying roll, means for supplying cement to the upper side of said roll including a casing surrounding the upper part of the roll, means for controlling the quantity of cement taken up by said roll for application to the work comprising an adjustable scraper having its forward edge arranged to be positioned adjacent to the periphery of said roll, means for determining the adjusted position of said

scraper, and means for preventing leakage of cement around the sides of said scraper comprising a tongue and groove connection between the lateral edges of the scraper and said casing.

7. In a cementing machine, a cement applying roll having a plurality of V-shaped grooves formed in its periphery, means for supplying cement to the upper side of said roll including a casing partially surrounding said roll to prevent the leakage of cement, adjustable means for controlling the quantity of cement taken out by the roll comprising a scraper having a notched edge approximating the cross-sectional outline of said roll, and means for determining the adjusted position of said scraper.

8. In a cementing machine, a cement applying roll, means for supplying cement to the upper side of said roll including a casing partially surrounding said roll, a U-shaped scraper slidably mounted in said casing and arranged closely to engage the sides of the roll and spaced from the periphery thereof to control the quantity of cement taken out by the periphery of the roll, and means for determining the adjusted position of the scraper.

9. In a cementing machine, a cement applying roll, means for supplying cement to the upper side of said roll including a casing partially surrounding said roll, a U-shaped scraper slidably mounted in said casing and arranged closely to engage the sides of the roll and to control the quantity of cement taken out by the periphery of the roll, means for preventing leakage between the scraper and the casing comprising tongue and groove joints between the sides of the scraper and the casing, and means for determining the adjusted position of the scraper.

10. In a cementing machine, a cement applying roll, means for supplying cement to the upper side of said roll including a casing partly surrounding the roll and leakage preventing plates pressed against the sides of the roll, a scraper slidably mounted in said casing for in and out movement, said leakage plates being cut away tightly to receive the scraper so that leakage between the plates and the scraper will be prevented without binding the scraper to prevent its adjustment as said plates are pressed against the sides of the roll.

11. In a cementing machine, a cement applying roll, means for supplying cement to the upper side of said roll including a casing partly surrounding the roll and leakage preventing plates pressed against the sides of the roll, and a U-shaped scraper cut out medially closely to fit said roll and to provide forwardly extending side arms, said leakage plates being notched to receive said side arms thereby to prevent leakage of cement.

12. In a cementing machine, a cement ap-

plying roll, means for supplying cement to the upper side of said roll, including a casing partly surrounding the roll and leakage preventing plates pressed against the sides of the roll, a scraper slidably mounted in said casing for in and out movement, said casing and the lateral edges of said scraper having a tongue and groove connection to prevent leakage of cement past the scraper, and said plates being notched to receive the lateral edges of the scraper beyond said tongue and groove connection.

13. In a cementing machine, a cement applying roll, means for supplying cement to the upper side of said roll including a casing partly surrounding the roll, a scraper slidably mounted in said casing for controlling the amount of cement taken out by the roll and provided with grooves above its lower edge, said casing having inwardly projecting tongues to enter said grooves to prevent the leakage of cement past the sides of the scraper.

14. In a cementing machine, a cement applying roll, means for supplying cement to the upper side of said roll including a casing partly surrounding the roll, a scraper slidably mounted in said casing for controlling the amount of cement taken out by the roll and provided with grooves above its lower edge, said casing having inwardly projecting tongues to enter said grooves to prevent the leakage of cement past the sides of the scraper, the contacting surfaces between the casing and the scraper adjacent to the outer surface of the casing being substantially vertical.

15. In a double cementing machine, superposed cement applying rolls, means for supplying cement to the upper side of the upper roll including a casing partially surrounding said roll, a U-shaped scraper slidably mounted in said casing to clean the cement from the sides of the upper roll and to control the amount of said cement carried by the periphery of said roll, a receptacle underlying and partially surrounding the lower roll, and a table overlying the ingoing side of the roll to support the work as it is introduced provided with a lateral flange overhanging the end of and adjustably mounted on said lower receptacle, said table portion having an edge arranged in proximity to the periphery of the roll to control the quantity of cement delivered thereby.

16. In a double cementing machine, superposed cement applying rolls, means for applying cement to the upper roll including a casing partially surrounding said roll, a scraper slidably mounted in said casing in horizontal relation and adjustable toward and away from the roll to control the quantity of cement applied thereby, a receptacle underlying and partially surrounding the lower roll, and means for guiding the work between said rolls comprising a table overhanging

the ingoing side of the roll and a guide member overlying said table having a portion arranged for engagement with the edge of the work to gage the position of the same, said overlying guide member being adjustable across the face of said table.

17. In a cement applying machine, a cement applying roll, a cement receptacle underlying said roll and having a table at the ingoing side of the roll, an adjustable guide member overlying said table and adjustable across the face of the table, said guide member having an upright surface for engagement with the edge of the work to guide it with respect to said cement applying roll, and a holdown flange mounted on the upright surface of said guide member.

18. In a cementing machine, a cement applying roll, a receptacle underlying and partially surrounding said roll the upper surface of which at the ingoing side of the roll is in a plane substantially tangential to the roll, and a work supporting table covering part of said receptacle and adjustably mounted upon the upper surface of said receptacle for movement along said tangential surface, the edge of which table is positioned in cooperative relation with the periphery of the roll to control the amount of cement taken up thereby, said table having a flange overhanging the end of the receptacle and provided with an elongated slot parallel to the surface of said table, and a retaining screw in said slot.

19. In a cementing machine, a cement applying roll, a receptacle underlying and partially surrounding said roll the upper surface of which at the ingoing side of the roll is in a plane substantially tangential to the roll, a work supporting table adjustably mounted upon said receptacle for movement along said inclined tangential surface, the edge of which lies in cooperative relation with the periphery of the roll to control the amount of cement taken up thereby, and a guide member adjustably mounted on said machine and overlying said table for movement in a direction parallel to the axis of rotation of said applying roll, said guide member having an upright surface for engagement with the edge of the work and an overlying portion for engagement with the upper margin of the work.

20. In a double cementing machine, superposed upper and lower cement applying rolls, means for supplying cement to the upper roll comprising a receptacle terminating in a casing partially surrounding the upper portion of said roll, a U-shaped scraper slidably mounted in said casing across the periphery of said roll so as completely to remove cement from the lateral faces of the roll and adjustable to control the quantity of cement carried out by the periphery of the roll, said lower cement applying roll being mounted

on an arm pivoted for movement toward and away from the upper roll and being narrower than said upper roll, a cement receptacle mounted on said arm and partially surrounding said lower roll, a combined scraper and work table mounted on said receptacle at the ingoing side of the roll, a combined edge gage and holddown adjustably mounted on said arm for movement across said table, and a yieldingly mounted work supporting arm pivotally mounted on said receptacle to underly the work to hold it against said upper roll where the upper roll overhangs the lower roll.

In testimony whereof I have signed my name to this specification.

CAROLINE E. COSGROVE,
*Administratrix of the Estate of John W. Cos-
grove, Deceased.*
